UNITED STATES PATENT OFFICE.

CARL H. HAUGK, OF BROOKLYN, NEW YORK, ASSIGNOR OF TWO-THIRDS
TO CARL VOGT AND CHARLES VOGT, BOTH OF SAME PLACE.

TEMPORARY WRAPPER FOR CIGARS.

SPECIFICATION forming part of Letters Patent No. 320,248, dated June 16, 1885.

Application filed June 14, 1884. (No model.)

To all whom it may concern:

Be it known that I, CARL H. HAUGK, of Brooklyn, county of Kings, and State of New York, have invented certain new and useful 5 Improvements in Temporary Wrappers for Cigars, of which the following is a specification.

The object of this invention is to furnish an improved temporary wrapper for the bunches 10 or fillers of cigars, by means of which not only the body, but also the tip and butt, receive their proper shape during the forming thereof in a suitable shaping-mold.

In the accompanying drawings, Figure 1 is 15 a perspective view of my improved temporary cigar-wrapper, and Fig. 2 is a view of a cigar-bunch with the wrapper applied thereto.

Similar letters of reference have been applied to corresponding parts in the different 20 figures.

A in the drawings represents a temporary wrapper for the bunches of cigars, which is made of paper of suitable size, and of a thickness sufficient to give the required strength 25 for the purpose for which it is intended to be used. This wrapper is composed of a single sheet of paper approximately rectangular in form, scalloped on opposite sides, and provided

with tongues *b* at opposite edges. It is applied to the cigar bunch or filler usually while 30 the latter is in a damp or moist condition. The bunch so wrapped is then placed in a suitable shaping or forming mold, as is customary in the manufacture of cigars. The body of the wrapper serves to hold in proper form the 35 body of the bunch, and the tongues *b* to hold the tip and butt thereof while in place in such mold.

I am aware that a temporary paper cigar-bunch wrapper provided with tongues for holding the tip of the cigar is shown in my German Patent No. 20,711, and I do not claim anything shown or described in said patent.

I claim as my invention—

A paper wrapper for cigar bunches, composed of a sheet approximately rectangular in form, and provided with scallops and tongues at opposite edges, which tongues serve to hold the tips and butts, substantially as described.

In testimony that I claim the foregoing as 50 my invention I have signed my name in presence of two subscribing witnesses.

CARL H. HAUGK.
